Thomas Donnelly
ATTORNEY.

UNITED STATES PATENT OFFICE

SALVATORE PATERNITI, OF DETROIT, MICHIGAN

SMOKE PRECIPITATING APPARATUS

Application filed June 15, 1929. Serial No. 371,188.

My invention relates to a new and useful smoke precipitating apparatus and particularly adapted for use in precipitating coal smoke.

5 The invention is so constructed as to operate so as to utilize the discharging effects of pointed surfaces of bodies possessing a high electric charge. It is known that by equipping a chimney or other passage-way 10 of smoke with a plate and discharging points positioned opposite thereto and a proper distance away from the plate and that by charging the apparatus to a high potential, precipitation of suspended particles from smoke 15 can be brought about. However, when the plate becomes covered with soot, the apparatus becomes ineffective and it is to overcome this disadvantage which is one of the objects 20 of the present invention.

20 Another object of the invention is the provision of a smoke precipitating apparatus of this class which will be simple in structure, economical of manufacture and highly efficient in use.

25 Another object of the invention is the provision of a device which may be easily and quickly installed, inexpensive to operate and compact in its structure.

Other objects will appear hereinafter.

30 The invention consists in the combination and arrangement of parts hereinafter described and claimed.

The invention will be best understood by a reference to the accompanying drawing 35 which forms a part of this specification and in which,

Fig. 1 is a central vertical sectional view of the invention.

Fig. 2 is a view taken on line 2—2 of Fig. 40 1, on a reduced scale.

Fig. 3 is a sectional view taken on line 3—3 of Fig. 2.

Fig. 4 is a sectional view taken on line 4—4 of Fig. 1.

45 Fig. 5 is a diagrammatic view illustrating the wiring used in the invention.

In the invention I provide a pair of standards 11 and 12 upon which are mounted, respectively, insulating blocks 11' and 12' which 50 serve to carry suitable bearings for the hori-

zontally extended shaft 13 which projects through insulating bushings 13' mounted in the walls 23 and 24 of a housing. Mounted so as to permit the shaft 13 to project therethrough is a housing having walls 15 and 18. 55 Projecting inwardly from the wall 15 is a cylindrical bracket 14 in which is positioned a spring 16 engaging a brush 20. A similar brush 21 is in engagement with the spring 19 positioned in the cylindrical bracket 17 60 which projects inwardly from the housing wall 18. In the lower part of this housing I have oil or a like liquid. Fixedly mounted on the shaft 13 so as to engage between and be engaged by the brushes 20 and 21 is a disc 22. The wall 24 of the housing is inwardly set as at 25 and provided with a vertically extending continuation 26. A neck 28 projects upwardly from the upper wall 27 of the housing embracing which is the conduit or flue 29 leading to the blower 30, this blower being operated by the electric motor 31. Fixedly mounted on the shaft 13 interiorly of the housing having the walls 23 and 24 is a disc 32. An insulating plate 33 serves to insulate the metallic plate 34 from the wall 26. Projecting outwardly from one face of the plate 34 so as to lie horizontally are metallic contact members or pins 36, preferably formed from wire, these pins projecting through the layer of insulation 35 which may be formed from asbestos wool or other suitable insulating material. Formed in this layer 35 is a cavity 37 in which is positioned the enclosing housing 38. Projecting inwardly from the housing wall 24 are brackets 39 and 40, each of which is constructed similarly. A slot 41 is formed in each of the brackets, these brackets being provided with channels 42 and 43 as appears in Fig. 1 and Fig. 4. Engaging in the channels 43 and 42 are trunnions 44 and 45, respectively, which project outwardly from the bearing 46 in which is journalled the shaft 47 of the roller brush 48, this roller brush being held by the springs 46' in engagement with the face of the disc 32. This brush is rotated by the flexible shaft 109 carrying the gear 110 which meshes with the gear 111 on the motor 68. 100

Projecting inwardly from the wall of the housing 38 are blades 49 and positioned adjacent the roller brush is a scraper blade 50. A sealing block 51 is positioned in the housing adjacent the periphery of the disc 32 so as to prevent passage of smoke around the disc 32 adjacent its upper end. A similar sealing block 52 is positioned around the insulating member 35. A conduit 53 which 5 serves as a flue or chimney is divided into a pair of branches 54 and 55 which communicate with the housing through the necks 56 and 57. Mounted in the flue 53 is a door 105 which is kept closed by the action of an electromagnet. In case the power should be accidentally cut off the electromagnet will release the door. Springs set for such purpose will push it wide open. The motive of such outlet is to give a way out to the smoke 15 for the time the power is off and the blower still. The wires 58 and 58' and 59 connect to a suitable source of electrical energy and lead to the transformer 60 which is electrically connected to the converter 61 which serves to 20 transmit direct current to the discharge points through a wire 62. A wire 63 connects this converter to the brushes 20 and 21 through the disc or plate 22 to the plate 32. The motors 68 and 31 are connected to the source of 25 electrical energy in the usual manner.

The motor 68 is connected by the belts 69 to the pulley 70 which is fixedly mounted on the shaft 13. The motors 31 and 68 are wired 30 to the mains in the regular way. A flexible shaft connects the rotary brush to the motor 68. Where a large machine is used a small motor may be used exclusively to rotate the brush, thus doing away with the flexible shaft.

40 In operation, as the smoke is delivered up the chimney 53, the electric charge will cause a deposit of the smoke over the disc 32. As the disc 32 is rotated upon a rotation of the shaft 13, the brush 48 will serve to prevent 45 accumulation of soot on the disc 32, thus providing an efficient operative device at all times.

While I have illustrated and described the 50 preferred form of my invention, I do not wish to limit myself to the precise details of structure shown but desire to avail myself of such variations and modifications as come within the scope of the appended claim.

55 Having thus described my invention, what I claim as new and desire to secure by Letters Patent is:

In a smoke precipitating apparatus of the 60 class described: a housing; an enclosing housing mounted in said housing; a circular metallic plate having a radial recess for reception of said enclosing housing; contact members projecting outwardly from said plate; a disc rotatably mounted in said housing and in spaced relation to said plate; and

a roller brush mounted in said enclosing housing and engaging the face of said disc.

In testimony whereof, I have signed the foregoing specification.
